ELECTRICAL COUPLING CIRCUIT

Application filed July 19, 1930. Serial No. 469,040.

This invention pertains to high-frequency electrical coupling circuits adapted to transfer energy throughout a range in frequency from an exciting circuit to a tunable absorbing circuit. The coupling circuit may be utilized for connecting an antenna system to the input of a radio receiver or for interconnecting successive stages of a high-frequency thermionic amplifier or radio receiver.

10 A primary object of the invention is to provide a coupling circuit of the type specified which in association with the elements connected thereby, will provide a sensitivity or amplification characteristic varying automatically with the frequency of tuning in a manner which is under control of the designer. More specifically the invention is intended to provide an approach toward uniform sensitivity throughout the tunable frequency range.

It is well known that the connection of an antenna system to a radio receiver or the interconnection of successive stages of a high-frequency thermionic amplifier by means of the usual high frequency transformers having tunable secondaries, results in an overall sensitivity characteristic which increases with frequency throughout the tuning range. This condition is undesirable since it renders an amplifying or radio receiving system most sensitive at the upper frequency limit where it is least stable. If the design is such as to insure adequate stability at the upper frequencies, the device becomes inefficient at the lower frequencies of tuning.

Attempts have been made to correct this condition by providing in shunt with the primary transformer winding a sufficient capacity to render the primary circuit resonant at a frequency below the tuning range, so that it is capacitively reactive and hence possesses an impedance characteristic decreasing with increase in frequency throughout the tunable range. This decrease in primary circuit impedance coupled with the automatic decrease in effective coupling between primary and secondary circuits, due to the shunting effect of the capacity, as the tuning frequency is increased, will operate to offset the natural tendency otherwise pres-

ent for the amplification to increase with frequency. It has been found, however, that this effect goes too far in the opposite direction, i. e., the sensitivity actually decreases with increase in tuning frequency.

55 The coupling circuit of the present invention proposes to overcome the above noted objections by utilizing a two-winding transformer for coupling a pair of thermionic tubes in cascade relation, for example, where in the primary circuit is rendered inductively reactive throughout the tuning range so that normally the sensitivity will increase with frequency. To partially offset this effect, a coupling condenser is connected between the primary and secondary terminals of like open-circuit polarity, as a result of which there will be provided between primary and secondary circuits a capacitive coupling which opposes the magnetic coupling between 60 windings throughout the tuning range.

65 It will be obvious with this arrangement that whereas the magnetic coupling between circuits will remain substantially constant throughout the frequency range, the capacitive coupling will increase steadily with the tuning frequency, and will thus oppose the effect of the magnetic coupling to a greater and greater degree as the upper frequency limit is approached. Thus, whereas the capacitive coupling has very little effect upon the amplification at the low frequency limit, it operates strongly to reduce the sensitivity otherwise present at the upper frequency limit and thereby provides an approach to 70 uniform sensitivity throughout the tunable range. It is thus possible to design the receiver for efficient amplification at the lower frequencies consistent with stable operation at the upper frequencies.

75 In order to provide a maximum opposing effect between the capacitive and magnetic couplings as the upper frequency limit is approached, it is desirable to arrange in shunt with the primary transformer winding 80 a sufficient capacity to render the primary circuit resonant at a frequency slightly above the tuning range. To this end the primary coil may be so wound that the various capacities naturally associated therewith, such as 85

the distributed capacity between turns, the coupling capacity between primary and secondary circuits, and the capacity of an antenna circuit or the anode-to-ground capacity of a thermionic tube connected thereto, will render the primary circuit resonant at the desired frequency.

Referring now to the drawing, Figure 1 shows in diagrammatic form a radio receiver employing the coupling circuits of the present invention for connecting the antenna circuit to the receiver input and for interconnecting successive stages thereof.

Figure 2 shows a series of graphs indicating the manner in which the sensitivity varies with the frequency of tuning for various coupling circuits in accordance with the present invention.

Fig. 3 shows a coupling circuit in accordance with the present invention interposed between thermionic tubes of the three electrode type wherein the coupling transformer is provided with a neutralizing winding and associated condenser for neutralizing the grid-cathode tube capacity.

In the circuit of Figure 1, an antenna 1 and ground 2 are connected to opposite terminals of a variable resistance 3, the voltage drop across which is impressed through a coupling circuit A_1 upon the input section comprising grid and cathode of a thermionic tube V_1 of the screen grid type operating as a stage of radio-frequency amplification. In the case of the antenna coupling system, the primary circuit being resonant above the tunable frequency range will be capacitively reactive throughout the range. The output section comprising anode and cathode of tube V_1 is connected through a coupling network A_2 to the input section of a second tube V_2 also operating as a stage of radio-frequency amplification. The output of tube V_2 is connected through the usual detector and audio-frequency amplifier D to a loud speaker L . The proper operating potentials for tubes V_1 and V_2 are supplied over conductors 4 while condensers f serve to by-pass the radio-frequency currents around the voltage supply circuit. The filaments of the tubes may be heated by any of the well-known methods (not shown).

Each coupling circuit A includes a transformer T having separate magnetically coupled primary and secondary windings L_1 and L_2 . In shunt with the secondary winding is a variable condenser C_2 which serves to tune the circuit over a range in frequency, specifically the broadcast band. The condensers C_2 are mechanically coupled for simultaneous adjustment by means of the unicontrol device U .

The primary and secondary windings are in each instance arranged to have their ungrounded terminals of like open-circuit polarity so that by connection of a coupling

capacity C therebetween, a capacitive coupling will exist between primary and secondary circuits which opposes the effect of the magnetic coupling therebetween for the condition that the primary circuit is inductively reactive throughout the tunable frequency range, (except when the coupling system is a part of the antenna circuit as previously explained) the coupling capacity C being sufficiently small that the current flowing therethrough is in phase opposition to the current of the primary circuit.

As the tuning condenser C_2 is adjusted for higher frequencies, the magnetic coupling M remains substantially constant, whereas the opposing capacitive coupling due to C steadily increases. The combination of these two factors causes the resultant effective coupling between primary and secondary circuits automatically to decrease with increase in tuning frequency and thereby to offset in part the normal tendency for the sensitivity to increase with frequency.

In order to render the effect of the opposed capacitive and magnetic couplings more pronounced as the upper frequency limit is approached, the effective inductance of the primary winding L_1 may be tuned by means of the capacities associated therewith to a frequency slightly above the upper frequency limit of tuning. The effective inductance of the primary winding is the magnitude thereof obtained with the secondary winding short-circuited and is, in fact, equal to $(1 - K^2) L_1$, where L_1 is the inductance of the primary with the secondary on open circuit, and K is the coefficient of magnetic coupling between circuits.

In the case of the coupling circuit A_1 the capacities operating to render the primary circuit resonant at a frequency above the tuning range are (1) the capacity to ground of the antenna system proper, (2) the distributed capacity between turns of the primary winding L_1 , and (3) the capacity of the coupling condenser C to ground through the tuning and by-passing condensers C_2 and f , respectively, which latter are so large in comparison with C that their effects may be neglected, and (4) any stray capacitive effects existing between the terminals of the primary winding.

In Figure 1 all of the capacities existing across the primary winding L_1 with the exception of the coupling capacity C are indicated by the lumped capacity C_1 . The total capacity thus associated with the primary winding should be sufficient to tune the primary circuit slightly above the tuning range, and if the capacities naturally associated with the primary winding are not sufficient to this end, a supplemental condenser may, of course, be connected thereacross.

In the interstage coupling circuit A_2 the primary circuit is tuned to resonance above

the tuning range by means of the coupling capacity C , the distributed capacity between turns and the anode-to-ground capacity of tube V_1 connected thereto, these latter two capacities together with any stray capacitive effects being indicated by the lumped capacity C_1 .

The coupling capacities C may comprise physical condenser units or the primary and secondary transformer windings may be so wound and so positioned that the natural capacities existing between windings will produce the desired results.

Figure 2 shows a set of curves obtained experimentally depicting the manner in which the coupling capacity C controls the amplification per stage as the frequency of tuning is adjusted throughout the range. The upper curve $C=0$ represents the condition for zero coupling capacity and shows clearly the manner in which the sensitivity normally increases with frequency. The curves $C=w$, x and y in the order named, show the results obtained by utilizing coupling capacities of successively increasing magnitudes. From these curves it is apparent that the coupling capacity has substantially no effect on the sensitivity at the low-frequency end of the scale, but reduces it below its normal value by a steadily increasing amount as the frequency of tuning is adjusted toward the upper frequency limit. Within limits it is also apparent that the greater the coupling capacity, the more nearly a condition of uniform sensitivity is approached.

Other factors remaining constant, the coupling capacity cannot be increased in magnitude indefinitely with attendant improvements as regards uniform amplification. As pointed out above, the capacity C is one of the factors determining the resonance frequency of the primary circuit which must always be maintained of the order of the upper frequency limit, since otherwise the amplification will rise to a maximum value within the tuning range and then drop off sharply as the upper frequency limit is approached. This condition is shown for the curve $C=z$ wherein the coupling capacity is sufficiently large to render the primary circuit resonant within the tuning range.

In the modification of Fig. 3 a pair of thermionic tubes V_1 and V_2 of the three-element type are coupled in cascade relation by means of a coupling circuit A_3 the amplification or gain characteristics of which are similar to that of circuit A_1 and A_2 . In order, however, to neutralize the grid-anode capacity of tube V_1 transformer T_3 in addition to the primary and secondary windings L_1 and L_2 , is provided with a neutralizing winding L_N magnetically coupled thereto. The winding L_N is connected from the low potential terminal of winding L_1 through a neutralizing capacity C_N to the grid electrode of tube

V_1 . The neutralization is accomplished in the well-known manner described in Patent No. 1,533,858 to L. A. Hazeltine.

What is claimed is:

1. A high-frequency electrical coupling system tunable over a range in frequency comprising separate primary and secondary circuits, said circuits being coupled magnetically by means of primary and secondary transformer windings individual thereto, respectively, and coupled capacitively by means of capacity connecting said circuits, said capacitive coupling being arranged to oppose said magnetic coupling throughout said frequency range, and said primary transformer winding having in the operation of said system an effective capacity associated therewith rendering said primary circuit resonant at a frequency above the highest frequency of said tuning range. 70

2. A high-frequency electrical coupling system tunable over a range in frequency comprising separate primary and secondary circuits, said circuits being coupled magnetically by means of transformer windings individual thereto and coupled capacitively by means of a condenser connecting a terminal of each winding, a conductive path extending between two remaining terminals of said windings, said capacitive coupling being arranged to oppose said magnetic coupling throughout said tunable range, and said primary winding in the operation of said circuit being arranged to have capacity associated therewith rendering said primary circuit resonant at a frequency above the highest frequency of said tunable range. 85

3. A high-frequency electrical coupling system tunable over a range in frequency comprising separate primary and secondary circuits, said circuits being coupled magnetically by means of primary and secondary transformer windings individual thereto, respectively, and coupled capacitively by means of a condenser connected between winding terminals of like open-circuit polarity, said primary winding in operation of said system having capacity associated therewith rendering said primary circuit resonant at a frequency slightly above the highest frequency of said tunable range, whereby the voltage amplification of said system remains substantially uniform as the tuning frequency is adjusted throughout said range. 100

4. A high-frequency electrical coupling system for interconnecting elements of a radio receiving system comprising a transformer having separate magnetically coupled primary and secondary windings, a variable condenser bridging said secondary winding for tuning the system over a range in frequency, a capacity connecting terminals of said windings of like open-circuit polarity, and a conductive path extending between two remaining terminals thereof, said pri- 115

- mary winding in the operation of said device having capacity associated therewith rendering the primary circuit resonant at a frequency slightly above the highest frequency of the tuning range, whereby said capacitive coupling opposes said magnetic coupling between windings and the amplification produced by said system approaches uniformity throughout said tunable range. 75
5. In combination, an electrical coupling circuit interconnecting an antenna circuit with the input section of a thermionic tube in a radio receiver, said coupling system comprising separate magnetically coupled primary and secondary transformer windings connected to said antenna and said tube respectively, a variable condenser bridging said secondary winding for tuning said circuits over a range in frequency, a capacitive coupling extending between said windings arranged to oppose said magnetic coupling throughout said tunable range, and capacity including the capacity of said antenna and of said capacitive coupling associated with said primary circuit rendering the primary circuit resonant at a frequency above the highest frequency of said frequency range. 80
10. 6. In combination, a radio-frequency coupling circuit interposed between elements of a thermionic tube radio-frequency amplifier, said circuit comprising separate magnetically coupled primary and secondary transformer windings connected to said elements respectively, a variable condenser associated with said secondary for tuning said circuit over a range in frequency, a capacitive coupling extending between said windings arranged to oppose said magnetic coupling throughout said frequency range, and capacity associated with said primary winding rendering the primary circuit resonant at a frequency of the order of the upper limit of said tunable range. 85
15. 7. In combination, a pair of thermionic tubes, each including cathode and grid constituting an input section, and an anode and said cathode constituting an output section, a high-frequency electrical coupling circuit connecting the output section of one said tube to the input section of the other, said circuit comprising separate magnetically coupled primary and secondary windings connected to said sections, respectively, a variable condenser bridging said secondary winding for tuning said circuit over a range in frequency, a capacitive coupling extending between said windings arranged to oppose said magnetic coupling throughout said frequency range, the effective inductance of the primary winding being such, in conjunction with the capacity associated therewith which includes the anode-to-cathode capacity of the tube connected thereto and said coupling capacity, as to render the primary cir- 90
